(57) CLAIM

The ornamental design for a cosmetics brush, as shown and described.

DESCRIPTION

FIG. 1 is a front plan view of the present design a cosmetics brush.

FIG. 2 is a side plan view of the cosmetics brush shown in FIG. 1.

FIG. 3 is a rear plan view of the cosmetics brush shown in FIG. 1; and,

FIG. 4 is a rear perspective view of the cosmetics brush shown in FIG. 1.

The broken lines showing the remainder of the ferrule and the handle illustrate portions of the cosmetic brush that forms no part of the claimed design.
